(57) **CLAIM**

The ornamental design for a light diffuser, as shown and described.

DESCRIPTION

FIG. 1 is a perspective view of the light diffuser showing my new design;

FIG. 2 is a front elevational view thereof, the rear elevational view being a mirror image;

FIG. 3 is a right side elevational view thereof, the left side elevational view being a mirror image;

FIG. 4 is a top plan thereof; and,

FIG. 5 is a bottom plan view thereof.

The break lines in FIGS. 1-2 and 4-5 are to indicate that the appearance of any portion of the light diffuser between break lines forms no part of the claimed design.

The broken lines shown in the drawings are included for the purpose of illustrating portions of the article that form no part of the claimed design.
